SEALING RING FOR ROTARY KILNS

Fred A. Mertz, Allentown, Pa., assignor to Traylor Engineering & Manufacturing Company, Allentown, Pa., a corporation of Delaware

Application October 29, 1946, Serial No. 706,439

18 Claims. (Cl. 285—10)

1

The present invention relates to rotary kilns of the type used in the manufacture of Portland cement and the like. More particularly, the invention is concerned with improvements in the sealing means between the end of a rotary kiln and the normally stationary firing hood, positioned adjacent thereto.

In the past, various types of seals have been provided between the ends of rotary kilns and the adjacent firing hoods, but numerous difficulties and disadvantages have been encountered in their use. One of the most generally-used constructions consists of a pair of flanged rings carried by the kiln and hood respectively, making a substantially running contact or spaced apart a predetermined distance, for the admission of currents of atmospheric air, tending to maintain the end of the kiln shell at reasonably cool temperatures, to prevent overheating and burning out of the same. In such constructions however, it has been necessary to advance and retract the firing hood with respect to the rotary kiln, to compensate for axial expansion and contraction of the latter under the influence of temperature changes. Even though the firing hood be mounted on track supported wheels, the adjustment of the hood and its associated parts is a laborious and troublesome operation. Moreover, difficulty is encountered in maintaining the space between the fixed and rotatable rings constant during the operation of the apparatus, and nicety of adjustment in this connection has been difficult or impossible to accomplish.

One of the primary objects of the present invention is to overcome the difficulties encountered in the use of prior art seals between the ends of rotary kilns and the adjacent stationary firing hood.

A further object is to provide a construction in which the hood need not be moved to compensate for expansion and contraction of the kiln, but in which the kiln is free to move axially, under the influence of temperature changes, relative to the firing hood.

A further object of the invention is to provide adjustable means for accurately determining the space between the fixed and movable parts of a seal for the end of a rotary kiln and associated firing hood. A further object is to provide a construction in which the space between the stationary and rotatable parts will not vary during the operation of the apparatus, in the event of expansion or contraction of the kiln, resulting from temperature changes.

Another object of the invention is to provide

2

a seal of the type described in which the parts are constantly maintained in the desired, closely fitting relation by the influence of gravity, working on one part and tending to move the same toward the other.

A further object is to provide long lasting, efficient, anti-friction connections between the fixed and movable parts, thereby reducing wear and other adverse factors.

10 Another object of the invention is to provide an improved sealing ring, loosely encircling the kiln at the discharge end, so connected thereto that the ring is caused to rotate with the kiln but is free to have relative axial movement with respect thereto.

Another object is to provide a seal, comprising fixed and rotatable rings so arranged that the end of the kiln is capable of axial movement through the rings, upon axial expansion and contraction of the kiln, resulting from temperature changes.

Other and further objects and advantages of the invention will be apparent from the following description of a specific embodiment shown in the accompanying drawings, in which

Figure 1 is a side elevation and partial vertical section of an apparatus embodying the invention.

Figure 2 is a transverse section, on an enlarged scale, taken substantially on the line 2—2 of Figure 1.

Figure 3 is a vertical sectional view through the seal shown in elevation in Figure 1, looking in substantially the opposite direction.

35 Figure 4 is a fragmentary top view of the construction shown in Figure 3, and

Figure 5 is a detail taken substantially on line 5—5 of Figure 2.

40 As is well understood in the art, a rotary kiln, having a cylindrical metallic shell 10 and a thrust ring 11 may be supported for rotation on an inclined axis by suitable supporting rollers 12 and thrust rollers 13. Such kilns are usually lined with refractory material 15, such as brick-work, and deliver the material during the calcining from the lower, discharge end 17. The latter

45 end of the kiln is enclosed by a firing hood 20, also constructed of refractory material and preferably mounted on rollers 21, 22, for relative movement toward and from the end of the kiln. Gas or other flame producing material is introduced through the hood and the heat thereof travels upwardly through the kiln, counter current to the downwardly moving material. A

50 stack or the like, positioned at the opposite end

of the kiln maintains a sub-atmospheric pressure in the kiln and firing hood, all as is well understood in the art.

Means must be provided to prevent the uncontrolled inflow of cool atmospheric air into the space between the stationary firing hood and the lower end of the rotatable kiln. In the past, rings or circumferential flanges fixed to the hood and kiln respectively have been employed, but such constructions make it necessary to adjust the position of the firing hood quite nicely with respect to the end of the kiln, a difficult operation, in view of the fact that long kilns, ranging up to 300 feet in length, expand and contract as much as three to six inches in length.

In accordance with the present invention, the lower end of the kiln is provided with a cylindrical metal shell and nose piece 25, made of a plurality of sections and secured in place by any suitable means. Around the shell 25, there is loosely fitted a ring 26, consisting of a cylindrical inner portion 27 and a radially outwardly projecting flange 28, connected together by appropriate integral webs 29. As indicated in Figure 2, the ring is preferably made in two semi-circular, cast iron or steel sections, secured together by bolts and nuts 30, extending through the jointing webs 31, 32, thereof.

The forward face 34 of the flange 28 is preferably circumferentially stepped back, as at 35, for the reception of an annular plate 36, held in place by countersunk screws 37 and nuts 38 projecting rearwardly through the flange.

The rear face of the flange 28 has formed integrally therewith a plurality of pairs of blocks 40, 41, having arcuate seats 42 formed therein, for purposes hereinafter explained.

The flange 28, in the spaces between the blocks 40 and 41 is provided with circumferentially elongated apertures or slots 43, and the ring 36 is provided with similar slots 44, registering therewith.

Rollers 45 having central bearings 46 are journaled upon the central portions of stub shafts 47, having reduced, eccentric end portions 48, 49 seated upon the arcuate seats 42 formed in the blocks 40, 41 and held in place, against inadvertent rotation by caps 50, adapted to be pulled down tightly by bolts 51, 52, threaded into appropriate bores formed in the blocks 40, 41. The radially outer ends 53, of the stub shafts are squared, or otherwise shaped for the reception of a wrench, for angular adjustment of the shafts when the bolts 51, 52 are loosened slightly. Conventional lubricant fittings 54 may be screwed into the ends of internal passages (not shown) in the shafts, to deliver grease to the bearing surfaces of the rollers 45, in the well known manner.

As noted above the ring 26 loosely encircles the lower discharge end of the kiln, so that there is no binding between the parts upon expansion and contraction, due to changes in temperature and the like, and so that the ring may move longitudinally with respect to the kiln. This loose fit is indicated, diagrammatically by the space 24, Figure 3. Means for assuring that the ring rotates with the kiln are provided, in the form of a chain 55 connected at one end to a clip 56, welded to the shell 25 and at the other to an eye bolt 57, threaded into an appropriate bore 58 in the cylindrical lower flange 27 of the ring 26. Hence, as the kiln rotates in the direction of the arrow in Figure 2, the ring is caused to rotate therewith by the chain 55, but relative axial

movement between the ring and the kiln is permitted, by reason of the flexibility of the chain.

The casing 60 of the hood 20 carries a ring plate 61, secured in place by countersunk bolts 62, extending through the casing and held in place by nuts 63 or the like. The ring 61 is of substantially the same diameter as and registers with the ring 36, but is non-rotatably carried by the firing hood.

By adjusting the angular positions of the stub shafts 47, in their seats 42, the rollers 45 may be projected through the slots 43 and 44, more or less, to extend beyond the front face 65 of the ring 36, to the desired extent, and to make rolling contact with the adjacent face 66 of the stationary ring 61 carried by the firing hood. Hence, the space 67 between the ring 36 and the ring 61 may be nicely adjusted, for the admission of controlled amounts of atmospheric air, into the firing hood, around the end of the rotary kiln, thus imparting just the desired cooling effect, without the introduction of large, uncontrolled amounts of cold air. Of course, this space 67 between the stationary and rotatable rings may be changed from time to time, by simply changing the angular adjustment of the stub shafts 47.

Due to the angle of inclination of the kiln as a whole and the loose connection between the ring assembly 26 and the kiln shell or nose piece 25, the ring tends to move downwardly toward the discharge end, under the influence of gravity, but the movement is resisted by the rolling contact between the rollers 45 and the stationary ring 61 carried by the hood. However, the end of the kiln as a whole is free to move axially through the rings 26 and 61, upon expansion and contraction thereof, resulting from changes in the temperature of the kiln.

It must be understood that the present invention is not limited to the details of construction shown in the accompanying drawings and described above, as many modifications and rearrangements of parts will readily occur to those skilled in the art, from a consideration of the illustrative embodiment of the invention shown and described. All modifications coming within the scope of the appended claims and their equivalents are intended to be included.

I claim:

1. A sealing connection for the discharge end of an elongated cylindrical rotary kiln of the type normally subjected to longitudinal expansion and contraction under the influence of temperature changes, and an adjacent normally stationary firing hood, said connection comprising an outwardly projecting ring encircling the kiln adjacent said end thereof, a similar ring carried by the hood, encircling the kiln and having a surface facing the first ring, one of said rings being movable axially with respect to the kiln to compensate for expansion and contraction thereof, and the other ring being relatively fixed, and a plurality of rollers carried by one of the rings, making rolling contact with the other, said rollers being journaled on axes disposed radially with respect to the kiln and being adjustable relative to the first ring to vary the clearance between the two.

2. A sealing connection for the discharge end of a rotary cylindrical kiln and an adjacent, normally stationary firing hood, comprising a pair of rings encircling said end of the kiln, one carried by the kiln for rotation therewith and the other carried by the hood, and a plurality of rollers carried by one ring, journaled on axes dis-

posed radially with respect to the kiln and having anti-friction, rolling contact with the adjacent surface of the other ring.

3. A sealing connection for the discharge end of a rotary cylindrical kiln and an adjacent, normally stationary firing hood, comprising a pair of rings encircling said end of the kiln, one carried by the kiln for rotation therewith and for limited axial movement with respect thereto, and the other carried by the hood in closely spaced relation to the first ring, and a plurality of rollers carried by the first ring, journalled on axes disposed radially with respect to the kiln and making rolling contact with the adjacent surface of the second ring.

4. A sealing connection for the end of a rotary cylindrical kiln and an adjacent normally stationary firing hood, comprising a ring loosely encircling the discharge end portion of the kiln, rotatable therewith and capable of limited relative axial movement thereon, another ring facing the first ring, carried by the hood, and anti-friction means carried by one of said rings making rolling contact with the other.

5. A connection for the lower discharge end of an inclined, rotary, cylindrical kiln and an adjacent normally stationary firing hood, comprising a ring loosely encircling said end of the kiln for limited axial movement with respect thereto, flexible connecting means between the ring and kiln, causing the ring to rotate with the kiln, and a second ring carried by the hood encircling said end of the kiln and positioned in juxtaposed relation to the first ring, whereby the first ring, under the influence of gravity tends to move toward the second as the kiln rotates, expansion and contraction of the kiln through said rings being unrestrained.

6. A connection for the lower discharge end of an inclined, rotary cylindrical kiln and an adjacent normally stationary firing hood, comprising a radially outwardly projecting ring loosely encircling the kiln and normally urged toward said end by gravity as the kiln rotates, a second ring carried by the hood disposed in juxtaposed relation to the first ring, and a plurality of rollers carried by the first ring making anti-friction rolling contact with the second.

7. A connection for the lower discharge end of an inclined, rotary cylindrical kiln and an adjacent normally stationary firing hood, comprising a radially outwardly projecting ring loosely encircling the kiln and normally urged toward said end by gravity as the kiln rotates, a second ring carried by the hood disposed in juxtaposed relation to the first ring, and a plurality of rollers journalled on axes disposed radially with respect to the kiln, carried by the first ring and making rolling contact with the surface of the second ring.

8. A connection for the lower discharge end of an inclined, rotary cylindrical kiln and an adjacent normally stationary firing hood, comprising a ring encircling the discharge end of the kiln and having a continuous radially outwardly projecting, slotted flange, a second ring encircling the said end of the kiln carried by the hood having a continuous surface parallel to and facing said flange, and a plurality of rollers carried by the first ring having their peripheries projecting through the slots in the flange and making rolling contact with the second ring.

9. A connection between the discharge end of a rotary cylindrical kiln and an adjacent, normally stationary firing hood, adapted to admit

controlled amounts of atmospheric air into the hood and kiln, comprising a ring surrounding said end of the kiln, mounted for limited axial movement with respect thereto, urged toward said end thereof and rotatable therewith, a second ring carried by the hood and facing the first ring, and a plurality of circumferentially spaced rollers carried by the first ring, journalled on axes disposed radially with respect to the kiln and engaging the surface of the second ring with rolling contact, said rollers serving to space the first ring from the second a predetermined distance for the admission of a predetermined flow of atmospheric air therebetween.

10. A connection between the lower discharge end of an inclined rotary cylindrical kiln and an adjacent normally stationary firing hood, adapted to admit controlled amounts of atmospheric air into the hood and kiln, comprising a ring loosely encircling the kiln, tending to move axially toward said end under the influence of gravity as the kiln rotates, a second ring carried by the hood, encircling the kiln in spaced relation thereto and facing the first ring, and a plurality of circumferentially spaced, axially adjustable rollers carried by the first ring, making rolling contact with the surface of the second ring and spacing the rings apart a predetermined distance, depending upon their adjusted positions, for the admission of a predetermined, variable air flow therebetween.

11. A connection between the lower discharge end of an inclined rotary cylindrical kiln and an adjacent normally stationary firing hood, adapted to admit controlled amounts of atmospheric air into the hood and kiln, comprising a ring loosely encircling the kiln, tending to move axially toward said end under the influence of gravity as the kiln rotates, a second ring carried by the hood, encircling the kiln in spaced relation thereto and facing the first ring, and a plurality of circumferentially spaced rollers carried by the rear surfaces of the first ring with their peripheries projecting axially beyond the other face thereof and making rolling contact with the adjacent face of the second ring and spacing the rings a predetermined distance apart for the admission of a predetermined flow of atmospheric air therebetween.

12. A connection between the lower discharge end of an inclined rotary cylindrical kiln and an adjacent normally stationary firing hood, adapted to admit controlled amounts of atmospheric air into the hood and kiln, comprising a ring loosely encircling the kiln, tending to move axially toward said end under the influence of gravity as the kiln rotates, a second ring carried by the hood, encircling the kiln in spaced relation thereto and facing the first ring, and a plurality of circumferential spaced rollers journalled on shafts adjustably mounted behind the first ring with their peripheries projecting variable distances beyond the other face thereof and making rolling contact with the adjacent face of the other ring and spacing the rings apart a predetermined, variable distance for the admission of predetermined variable currents of atmospheric air therebetween.

13. A connection between the lower discharge end of an inclined rotary cylindrical kiln and an adjacent normally stationary firing hood, adapted to admit variable, controlled amounts of atmospheric air into the hood and kiln, comprising a ring loosely encircling said end of the kiln, having a radially outwardly projecting, slotted flange, said ring being urged toward said end by

gravity as the kiln rotates, a second ring carried by the hood, encircling said end of the kiln and having a surface facing the flange of the first ring and a plurality of rollers carried by the ring, journaled behind said flange with their peripheries projecting through the slots therein and beyond the other face of the flange and making rolling contact with said surface of the second ring, said rollers serving to space the first ring from the second a predetermined distance for the admission of a predetermined flow of atmospheric air therebetween.

14. A connection between the lower discharge end of an inclined rotary cylindrical kiln and an adjacent, normally stationary firing hood, adapted to admit variable, controlled amounts of atmospheric air into the hood and kiln, comprising a ring loosely encircling said end of the kiln, having a radially outwardly projecting, slotted flange, said ring being urged toward said end by gravity as the kiln rotates, a second ring carried by the hood, encircling said end of the kiln and having a surface facing the flange of the first ring, and a plurality of circumferentially spaced rollers adjustably carried by the first ring, journaled on axes disposed radially with respect to the kiln, projecting through said slots and beyond the surface of the flange and engaging the second ring by rolling contact, the adjustment of said rollers serving to vary the space between said rings and thereby to vary the amount of atmospheric air flowing into the hood and kiln.

15. A connection between the lower discharge end of an inclined rotary cylindrical kiln and an adjacent normally stationary firing hood, comprising a ring having an inner cylindrical surface loosely encircling said end of the kiln and a radially outwardly projecting flange having a plurality of slots therein, a pair of shaft-holding blocks adjacent each slot, a shaft having eccentric ends seated upon each pair of blocks, means for clamping said ends upon said blocks against rotation, a roller on each shaft projecting through the adjacent slot and therebeyond a distance determined by the angular adjustment of the shaft, and a second ring carried by the hood, facing the flange of the first ring, positioned to be engaged by said rollers, whereby the rollers space the first ring from the second a predetermined, variable distance, depending upon the angular adjustment of said shafts.

16. A sealing connection for the lower discharge end of a rotary cylindrical kiln and an adjacent normally stationary firing hood, comprising a ring having a circumferential portion loosely encircling said end and a radially outwardly pro-

jecting, circumferentially continuous, slotted flange, a pair of shaft seats adjacent each slot, a stub shaft having eccentric ends mounted in each pair of seats, a roller on each shaft projecting through the adjacent slot a variable distance depending upon the angular adjustment of the shafts in said seats, and a stationary ring carried by the hood facing the first mentioned ring and around which the rollers travel by rolling contact.

17. A connection between the lower discharge end of an inclined rotary cylindrical kiln and an adjacent normally stationary firing hood, comprising a ring casting having an inner, circumferential flange loosely encircling said end of the kiln and an integral radially outwardly projecting, circumferentially continuous, slotted flange, an annular plate secured to the front face of the last mentioned flange, having slots therein registering with the flange slots, a pair of shaft seats adjacent to and behind each flange slot, a stub shaft having eccentric ends mounted in each pair of seats, a roller on each shaft projecting through the adjacent flange and plate slots a variable distance, depending upon the angular adjustment of the shaft in said seats, a flexible tension element connecting the inner flange of the ring to the kiln, causing the ring to rotate with the kiln, but permitting relative axial movement therebetween, and a stationary ring carried by the hood facing the annular plate and around which the rollers travel by rolling contact.

18. A sealing connection for the discharge end of a rotary cylindrical kiln and an adjacent, normally stationary firing hood, comprising a ring carried by the hood encircling said end of the kiln, a second ring loosely encircling the kiln for axial movement with respect thereto, connecting means between the kiln and the second ring for causing the latter to rotate with the kiln, and a plurality of rollers journaled on axes disposed radially with respect to the kiln, carried by one of the rings and making rolling contact with the adjacent surface of the other ring.
